(57) CLAIM

(22) Filed: **Dec. 7, 2001**

The ornamental design for an electrical connecting socket, as shown and described.

(30) Foreign Application Priority Data

DESCRIPTION

Jun. 19, 2001 (JP) 2001-021571

FIG. 1 is a perspective view of an electrical connecting socket according to the present invention;

(51) LOC (7) Cl. **13-03**

FIG. 2 is a top plan view of the electrical connecting socket according to the present invention;

(52) U.S. Cl. **D13/147**

FIG. 3 is a bottom plan view of the electrical connecting socket according to the present invention;

(58) Field of Search D13/146, 147; 439/108, 607, 609

FIG. 4 is a front elevation view of the electrical connecting socket according to the present invention;

(56) References Cited

FIG. 5 is a rear elevation view of the electrical connecting socket according to the present invention;

U.S. PATENT DOCUMENTS

FIG. 6 is a right side elevation view of the electrical connecting socket according to the present invention; and,

D391,551 S * 3/1998 Ono D13/147
D425,027 S * 5/2000 Nishio et al. D13/147
D433,665 S * 11/2000 Huang D13/147
D433,666 S * 11/2000 Yang D13/147
D434,382 S * 11/2000 Shimojyo D13/147
D449,821 S * 10/2001 Shimojyo D13/147
D452,481 S * 12/2001 Shimojyo D13/147

FIG. 7 is a left side elevation view of the electrical connecting socket according to the present invention.
